[57] CLAIM

The ornamental design for a tie for masonry and brick, as shown and described.

DESCRIPTION

FIG. 1 is a perspective view of a tie for masonry and brick showing our new design, the first component on the left and the wall being shown in broken lines for illustrative purposes only;

FIG. 2 is an enlarged top perspective view of the first component shown separately for ease of illustration, the side opposite being a mirror image and the bottom being unornamented; and,

FIG. 3 is a top perspective view of the second component shown separately for ease of illustration, the side opposite being a mirror image and the bottom being unornamented.

FIG. 1

FIG. 2
